PRODUCTION OF ORGANIC SULPHUR COMPOUNDS

Alva C. Byrns, Palos Verdes Estates, Calif., assignor to Union Oil Company of California, Los Angeles, Calif., a corporation of California

No Drawing. Application February 12, 1940,
Serial No. 318,631

8 Claims. (Cl. 260—609)

This invention relates to a process for separating and recovering organic sulphur compounds from hydrocarbon fractions containing the same.

In a more specific sense the invention is concerned with a process for selectively extracting sulphur compounds from petroleum fractions in which they are present and the isolation and recovery of these sulphur compounds in usable form from the extracts.

It is well known that petroleum crude oil distillates contain various types of organic sulphur compounds. The amounts and types of these sulphur compounds present in any particular distillate fraction will depend primarily on the source of the crude oil and previous treatment such as distillation, cracking, contact with sulphuric acid, contact with caustic soda solution, etc. For example, it has been shown that fractions derived from any petroleum crude oil by distillation and boiling over a range of 100° F. to 400° F. will contain varying proportions of mercaptans, alkyl sulphides, alkyl disulphides, thiophenes and thio-

It has been recognized that sulphur compounds of acidic character, such as the mercaptans, can be more or less readily removed and recovered from petroleum distillates by treatment of the latter with aqueous caustic soda solution and subsequent acidification of the separated aqueous phase. However, such a treatment fails to remove any of the alkyl sulphides, alkyl disulphides, thiophenes and thiophenes which are present in many petroleum distillates in appreciable proportions, particularly in those boiling above about 200° F. Treatment with strong sulphuric acid serves to remove sulphur compounds from petroleum distillates but the sulphur compounds cannot be recovered from the acid sludge. Some attempts have been made to extract selectively the non-acidic organic sulphur compounds present in petroleum distillates by the use of mercuric chloride. A number of investigators have reported that mercuric chloride forms complexes with various organic sulphur compounds, such as those present in petroleum distillates, but that these complexes were so stable that they could be decomposed only with difficulty and with low yields of sulphur compounds.

It is an object of my invention to extract selectively organic sulphur compounds from petroleum distillates. It is another object to recover the sulphur compounds in usable form from the extracts. It is an additional object of the pres-

ent invention to produce petroleum distillates of relatively low sulphur content.

I have now discovered that at ordinary atmospheric temperatures, anhydrous aluminum chloride readily forms complexes with various types of organic sulphur compounds such as those commonly found in petroleum fractions; namely, thiophanes, alkyl sulphides, alkyl disulphides, etc. These complexes are apparently not of definite chemical composition but may comprise one or more molecules of aluminum chloride in combination with one or more molecules of the sulphur compounds. The complexes formed when one mol of aluminum chloride is present for each mol of sulphur compound are fairly fluid at the usual atmospheric temperatures, are relatively insoluble in hydrocarbons boiling below about 500° F., particularly the lower molecular weight paraffin hydrocarbons, and are readily decomposed by water to yield an aqueous phase containing hydrated aluminum chloride and an oily phase containing the sulphur compounds. As the molal proportion of aluminum chloride to sulphur compound is increased from 1 to 1 up to 5 to 1 or even 10 to 1 the solubility of the resulting complex in petroleum hydrocarbons decreases. On the other hand as the molal proportion of aluminum chloride to sulphur compound decreases below 1 to 1, the solubility of the resulting complex in petroleum hydrocarbons increases.

The fluidity of a complex of any given molar proportion of aluminum chloride to sulphur compound increases as the temperature is increased. However, where it is desired to avoid any excessive decomposition of the sulphur compounds in the complex, the latter should not be heated to temperatures much in excess of 125° F. and definitely not in excess of 150° F. At more elevated temperatures decomposition of the sulphur compounds is observed and hydrogen sulphide is liberated. At temperatures much below about 30° F. the aluminum chloride-sulphur compound complexes become extremely viscous.

The aluminum chloride-sulphur compound complexes are readily decomposed either by water or by dilute aqueous acid solution. The use of the dilute aqueous acid solutions, such as dilute hydrochloric or acetic acid solution, for hydrolysis of the complexes to recover organic sulphur compounds is preferred as hydrolysis of the aluminum chloride to aluminum oxychloride is repressed and a more rapid separation of the oily sulphur compound phase from the aqueous phase is obtained. In the hydrolysis of the complex considerable heat is liberated and care must be

exercised that the temperature of the mixture does not exceed about 125° F. and definitely must not exceed 150° F.

In view of the aforementioned properties of aluminum chloride-organic sulphur compound complexes, I have discovered that organic sulphur compounds can be selectively removed from petroleum fractions by treatment of the latter with anhydrous aluminum chloride at temperatures above about 30° F. but not much in excess of about 125° F. and below 150° F. and preferably in the range of 60 to 90° F. The amount of anhydrous aluminum chloride used to extract sulphur compounds from petroleum fractions may vary depending upon whether it is desired to effect a relatively complete removal of the sulphur compounds from the petroleum fraction or a more efficient utilization of the aluminum chloride. Preferably it is desired to treat petroleum fractions with about 4.0 pounds of aluminum chloride for each 1.0 pound of sulphur present in the form of organic sulphur compounds in order to obtain a relatively efficient utilization of the aluminum chloride and at the same time a maximum desulphurization of the petroleum fraction. Amounts of anhydrous aluminum chloride as low as about 2.0 pounds and as high as 20 to 30 pounds per pound of sulphur present in the form of organic sulphur compounds can be employed where a more complete desulphurization of the particular petroleum fraction is desired.

The sulphur compounds can be selectively extracted from petroleum fractions by simply adding the required amount of aluminum chloride, intimately commingling the aluminum chloride and petroleum fraction at a temperature below 150° F. and subsequently allowing the complex formed to collect at the bottom of the container. The treated petroleum fraction can then be decanted and the sulphur compounds recovered by hydrolysis of the extract phase in the manner previously described.

However, in view of the fluid character of the aluminum chloride-organic sulphur compound complex, a more efficient utilization of the aluminum chloride can be obtained simultaneously with a more effective desulphurization of the petroleum fraction by contacting the aluminum chloride with the petroleum fraction in a countercurrent manner. That is, aluminum chloride is introduced into the top of a treating column and is allowed to descend against an upwardly moving stream of the petroleum fraction being treated.

In some instances a certain amount of the petroleum fraction may be mechanically occluded in the extract phase comprising the aluminum chloride-sulphur compound complex. This occluded material may be effectively removed by extraction of the complex with a low boiling hydrocarbon fraction such as pentane or butane. Any residual low boiling solvent remaining in the complex after extraction should be volatilized from the complex at a temperature below about 125° F.

It is, therefore, an object of the present invention to extract selectively organic sulphur compounds from petroleum fractions by treatment of the latter with anhydrous aluminum chloride in the proportion of 0.5 mol to 10.0 mols of anhydrous aluminum chloride per mol of organic sulphur compounds present in the petroleum fraction and subsequently to separate the extract phase from the treated petroleum fraction, said

treatment being conducted at a temperature above about 30° F. and below about 150° F. and preferably at a temperature in the range of 60° F. to 90° F. It is an additional object of the present invention to recover organic sulphur compounds in usable form from the separated aluminum chloride extract by hydrolysis of the latter with water or dilute aqueous acid solutions, and subsequent separation of the oily organic sulphur compound phase from the aqueous phase, the temperature of hydrolysis being maintained below 150° F. and preferably below about 125° F. It is a further object to obtain fractions comprising relatively pure sulphur compounds by fractional distillation of the recovered hydrolyzate.

In the foregoing specification it was observed that aluminum chloride-organic sulphur compound complexes are somewhat soluble in higher boiling petroleum fractions, particularly in those boiling above about 500° F. but are practically insoluble in the low boiling paraffin hydrocarbons. As a result, I have found that sulphur compounds can be effectively extracted from the higher boiling petroleum fractions by either diluting the said fractions with one or more volumes of a low boiling paraffin hydrocarbon such as, for example, propane, butane, or pentane and subsequent addition of the required amount of anhydrous aluminum chloride or treatment of the higher boiling petroleum fractions with the desired amount of anhydrous aluminum chloride and subsequent addition of one or more volumes of a low boiling paraffin hydrocarbon. Obviously, the above method need not be limited to the higher boiling petroleum fractions but can be applied if desirable to any petroleum fraction.

It is an object of the present invention to effect a more complete separation of organic sulphur compounds from petroleum fractions, particularly those boiling above about 500° F., by dilution of the said fractions with one or more volumes of a low boiling paraffin hydrocarbon either before or after treatment of the said fractions with anhydrous aluminum chloride.

Many petroleum fractions contain small amounts of acidic and basic compounds, such as, for example, naphthenic acids, phenols, nitrogen bases, etc. Many of these compounds will form complexes with aluminum chloride and if present in the petroleum fraction will be removed into the extract along with the sulphur compounds upon treatment with aluminum chloride. In order to conserve aluminum chloride and obtain organic sulphur compounds free of such acidic and basic materials, it is desirable to treat petroleum fractions successively with dilute sulphuric acid or other acidic material and caustic soda or other alkaline solution prior to treatment with anhydrous aluminum chloride in order to remove any basic and acidic materials, respectively, which may be present. On the other hand, if it is desired, the petroleum fraction may be first extracted with aluminum chloride and the hydrolyzate obtained washed successively with dilute acid and caustic soda solution in order to remove basic and acidic compounds, respectively, extracted from the petroleum fraction by the aluminum chloride.

In the foregoing specification and in the claims, the terms "petroleum fraction" and "petroleum distillate" are meant to include any material produced from a petroleum crude oil by distillation or extraction. Furthermore, it is meant to include materials produced from petro-

leum crude oil distillates by solvent extraction, such as, for example, a sulphur dioxide extract of kerosene or gasoline distillate. However, the terms are not meant to include materials produced by the cracking of petroleum fractions.

Other features, advantages and objects of the present invention will become apparent to those skilled in the art from the following specific examples:

Example 1

Twenty liters of a 400° F. end-point straight-run gasoline derived from Santa Maria Valley (California) crude oil by distillation, and having a gravity of 55.5° A. P. I. at 60° F. and a sulphur content of 0.61% was intimately mixed at atmospheric temperature with 600 grams of anhydrous aluminum chloride for a period of approximately two hours. The length of the period of agitation of the aluminum chloride with any given petroleum fraction is dependent upon the efficiency of the mixing and may vary from fifteen minutes to several hours depending upon the nature of the equipment. The mixture was allowed to stand for twelve hours in order to obtain complete separation of the extract phase. The treated gasoline was decanted from the separated extract which collected as a heavy tar in the bottom of the treating vessel. The refined gasoline, after being washed with dilute alkali had substantially the same boiling range as the untreated material and contained only 0.072% sulphur.

The separated extract was washed with pentane and subsequently hydrolyzed with ice to obtain 323 grams of an oil having a gravity of 25.1° A. P. I. and a sulphur content of 13.7%. An additional 52 grams of sulphur compounds were obtained by extracting the aqueous hydrolysis phase with pentane. In all, 375 grams of extract oil were obtained from the 20 liters of gasoline treated.

The extract oil was dried and a 250 ml. portion was fractionated into a number of cuts as follows:

Fraction	Boiling range	Dist. pressure mm. Hg	Vol.	Specific gravity at 60° F.	R. I. / 20° C.	Sulphur
Cut 1.....	° C. 70-90		ML. 760	56	0.8008	Per cent 0.88
2.....	90-137		760	10	1.4476	
3.....	137-165		760	14	1.4717	
4.....	40-62		8	48	0.9153	1.4826 20.7
5.....	62-75		8	45	0.9200	1.4876 19.5
6.....	75-88		8	34	0.9328	1.4932 18.1
7.....	88-101		8	20	0.9427	1.4902 16.7
Bottoms.....	>101		8	15		

It will be noted that cut 1 is low in sulphur content and is probably largely of hydrocarbon character. Cuts 4, 5, 6, 7 and the bottoms are higher in sulphur content than the crude extract. If the average molecular weight of cut 5 is assumed to be approximately 100, a reasonable assumption considering the boiling range of the material, it is readily seen that this fraction consists only of sulphur compounds. The compounds in this particular fraction have been found to be largely thiophanes.

Example 2

Two hundred and fifty milliliters of a heavy gas oil derived from Santa Maria Valley (California) crude oil by distillation, and having a gravity of 18.8° A. P. I. at 60° F. and a sulphur content of 3.82% was intimately mixed at at-

mospheric temperature with 37.5 grams of anhydrous aluminum chloride. On subsequent standing a small amount of extract separated but the oil phase remained dark colored. The decanted oil phase was diluted with cleaners naphtha, filtered, washed with water and the naphtha removed by distillation. The recovered oil had a sulphur content of 3.06% indicating that only a small proportion of the sulphur compounds had been removed.

The above experiment was repeated under somewhat different conditions. Seven hundred and fifty milliliters of the same gas oil was diluted with 500 milliliters of a hexane-heptane mixture and subsequently intimately mixed at atmospheric temperatures with 200 grams of anhydrous aluminum chloride for one hour. An additional 250 milliliters of the hexane-heptane mixture was then added and the material allowed to stand undisturbed for sixteen hours. The upper layer was then decanted, filtered, washed with water and the hexane-heptane mixture removed by distillation. The resultant treated oil had a sulphur content of only 1.83% and a gravity of 23.8° A. P. I. The separated aluminum chloride extract was hydrolyzed with dilute hydrochloric acid. The oil recovered from the hydrolyzate by topping to remove the hexane and heptane, had a gravity of 10.8° A. P. I. at 60° F. and a sulphur content of 6.91%.

Approximately 120 grams of the recovered extract oil was fractionated under a pressure corresponding to 2 mm. of mercury, six overhead cuts and a solid black residue being obtained.

Cut No.	B. P. °C at 2 mm. Hg	Wt. of cut	S.	
			Grams	Per cent by wt.
1.....	106-150	20.9		8.07
2.....	150-162	14.3		7.19
3.....	162-180	22.2		6.96
4.....	180-190	20.1		6.58
5.....	194-223	17.0		6.37
6.....	223-235	14.1		Not determined

Example 3

One liter of an aromatic hydrocarbon fraction having a gravity of 35.8° A. P. I. at 60° F. and a sulphur content of 0.043% and derived from the acid treatment of a sulphur dioxide extract of kerosene distillate, was intimately mixed at atmospheric temperature with 15 grams of anhydrous aluminum chloride. The mixture was allowed to stand undisturbed for several hours and the hydrocarbon phase then decanted, washed with water and dilute caustic soda. The treated oil had a sulphur content of only 0.005%. The extract oil recovered from the hydrolysis of the extract phase had a sulphur content of 2.73%.

The sulphur compounds removed from petroleum distillates find application as special solvents, as odorants, and for use in chemical synthesis. As an example of the latter the sulphur compounds present in cut 5 of Example 1 mentioned hereinabove have been converted into ketones which exhibit excellent solvent properties and may be useful as flotation agents.

The foregoing exemplary description of my invention is not to be considered as limiting since many variations may be made within the scope of the following claims by those skilled in the art without departing from the spirit thereof.

I claim:

1. A method of isolating sulphur compounds from petroleum which comprises treating petro-

leum with anhydrous aluminum chloride at a temperature not lower than 30° F. or in excess of 125° F. thereby forming an aluminum chloride-sulphur compound complex, recovering said complex from said petroleum, hydrolyzing said complex and separating the sulphur compounds from the aluminum residue in the same form as said sulphur compounds exist in the original petroleum.

2. A method of isolating sulphur compounds from petroleum which comprises reacting said petroleum with anhydrous aluminum chloride at a temperature of the order of 60 to 90° F. thereby forming a complex between the sulphur compounds contained in said oil and the aluminum chloride, separating said complex from the oil, hydrolyzing the complex with water to liberate the sulphur compounds and fractionating the sulphur compounds from the hydrolyzed mixture in the same form as said sulphur compounds exist in the original petroleum.

3. A method of isolating sulphur compounds from petroleum which comprises reacting said oil with anhydrous aluminum chloride in the proportion of one half to ten mols of aluminum chloride per mol of sulphur compound present in said oil and at a temperature between 30° F. and 125° F. thereby forming an aluminum chloride-sulphur compound complex, separating said complex from the petroleum, hydrolyzing said complex and fractionating the organic sulphur compound from the hydrolyzed mixture without any substantial change in structure of the sulphur compounds from the form in which they exist in the original petroleum.

4. A process as claimed in claim 1 in which a low boiling paraffinic hydrocarbon is added to the petroleum to aid in the separation of the aluminum chloride-sulphur compound complex from the oil.

5. A method of isolating sulphur compounds from a hydrocarbon fraction which comprises contacting said hydrocarbon fraction with anhydrous aluminum chloride at a temperature not substantially below 30° F. or substantially in excess of 125° F. and thereby forming a sulphur compound-aluminum chloride complex, removing said sulphur compound-aluminum chloride complex from the remaining hydrocarbon fraction, hydrolyzing said complex thereby liberating the sulphur compound contained therein and sep-

5 arating the liberated sulphur compound from the aluminum residue.

6. A method of isolating sulphur compounds from a hydrocarbon fraction which comprises diluting said fraction with a liquid hydrocarbon fraction having a boiling point not substantially higher than that of heptane, treating said diluted fraction with anhydrous aluminum chloride at a temperature not substantially lower than 30° F. or substantially higher than 125° F. and thereby forming an aluminum chloride-sulphur compound complex, removing said complex from the remaining hydrocarbon fraction, hydrolyzing said complex and thereby liberating the sulphur compound from said complex and separating the liberated sulphur compound from the aluminum residue.

7. A process for the recovery of sulphur compounds from a hydrocarbon fraction boiling at about 500° F. and above, which comprises diluting said hydrocarbon fraction with a liquid paraffinic hydrocarbon fraction having a boiling point not substantially higher than that of heptane, treating the diluted fraction with anhydrous aluminum chloride at a temperature not substantially lower than 30° F. or substantially higher than 125° F. and thereby forming an aluminum chloride-sulphur compound complex, separating the complex from the hydrocarbon fraction, hydrolyzing the complex thereby liberating the sulphur compound and recovering the liberated sulphur compound from the aluminum residue.

8. A process for the recovery of sulphur compounds from a hydrocarbon fraction which comprises diluting said fraction with a low boiling liquid hydrocarbon selected from the group consisting of propane, butane, pentane, hexane and heptane, contacting said diluted hydrocarbon fraction with anhydrous aluminum chloride at a temperature not substantially below 30° F. or substantially above 125° F. thereby forming an aluminum chloride-sulphur compound complex, separating the complex from the hydrocarbon fraction, hydrolyzing said complex thereby liberating the sulphur compound contained therein and recovering the liberated sulphur compound from the aluminum residue.
